HONE GAUGING DEVICE

Ricardo Mestas, Los Angeles, Calif., assignor to
 Kobe, Inc., Huntington Park, Calif., a corpora-
 tion of California

Application August 3, 1940, Serial No. 350,941

1 Claim. (Cl. 175—183)

My invention relates to honing devices, and more particularly to a honing device having gauge means provided to indicate the progress of the honing operation.

My invention is of particular utility in honing the interior of a tubular member, such as, for example, a piston cylinder, to a very close tolerance, and, consequently, for the purpose of illustration will be described in connection with such a use, although it will be appreciated that my device may be utilized in honing any kind of work as may be desired without departing from the spirit of my invention.

In honing a surface, and particularly the interior surface of a tubular member, it is standard practice to work a honing device on the surface for a period of time, then withdraw the honing device, and then apply a gauge to the surface to determine the progress of the honing operation. Where it is required to hone or finish a surface to close tolerances, this standard practice of working requires many time consuming gauging operations which are uneconomical and undesirable. Another disadvantage is that when the honing device must be withdrawn from the surface being honed to permit the gauging operation, as is frequently the case where the interior surface of a tubular member is being finished, it is sometimes difficult to re-engage the honing device with the surface being worked in exactly the same position as it occupied relative thereto prior to the gauging operation, thus causing unevenness in the subsequent honing operation. To obviate these disadvantages, it is a primary object of my invention to provide a method and apparatus for honing in which the extent of the honing operation may be measured and gauged during the honing operation and without withdrawing the honing device from the surface being honed. I prefer to accomplish this by providing a honing device having a gauge incorporated directly therein, with indicating means provided to indicate to an operator, in response to operation of the gauge, the progress of the honing operation.

It is also an object of my invention to provide a honing device having a gauge incorporated therewith for gauging the progress of the honing operation on a surface to be honed, and having an indicating means provided at a point remote from the honing device and operating in response to the operation of the gauge to indicate at the remote point the progress of the honing operation.

A further object of the invention is to supply

a device of the character specified in the preceding paragraph, in which the indicating means is connected to the gauge by electrical means and operated thereby.

5 Still another object of my invention is to provide a honing device having an electrical gauge means incorporated therewith adapted to operate in response to changes in a magnetic flux through a member formed of magnetic material being honed, caused by progress of the honing operation, to indicate the progress of the honing operation.

10 A further object of my invention is to provide a honing device for honing a non-magnetic material, having a gauge associated therewith operating in response to progress of the honing operation to indicate on a suitable indicating means during the progress of the honing operation the extent thereof.

15 Other objects and advantages will be apparent from the following specification and the drawings, which are for the purpose of illustration only and in which:

20 Fig. 1 is a vertical elevational view of my invention partly extending into a tubular member to be worked.

25 Fig. 2 is an enlarged cross-sectional view taken on the line 2—2 of Fig. 1.

30 Fig. 3 is a longitudinal sectional view taken on the line 3—3 of Fig. 2.

35 Fig. 4 is a diagrammatic view of the electrical circuit utilized in my device.

Fig. 5 is a longitudinal sectional view of an alternative embodiment of my invention.

40 Fig. 6 is a cross-sectional view taken on the line 6—6 of Fig. 5.

Referring to Figs. 1, 2, and 3 of the drawings, I show a tubular member 10 having a bore 11 therethrough, such as, for example, a pump cylinder, it being necessary to hone or otherwise grind the surface of the bore 11 to a desired diameter within close tolerances. Extending into the bore 11 of the tubular member 10 is a honing device 12.

45 The honing device 12 includes a head member 13 having a major bore 14 and a threaded minor bore 15 separated by a partition 16. Formed in the head member 13 so as to communicate with the major bore 14 thereof are a plurality of hone slots 17 radially disposed therein and preferably spaced equidistantly around the periphery of the head member. Also formed in the head member 13 are a pair of diametrically opposite gauge slots 18, each of which, as shown, is formed between adjacent hone slots 17. Disposed in each of the

hone slots 17 is a hone box 19 of approximately the same cross-sectional configuration as the hone slots but forming a relatively loose fit therein so as to be radially movable therein, each hone box 19 having a recess 20 therein in which is suitably secured a hone element 21 formed of "carborundum" or other suitable grinding material. As will be noted, each hone box 19 is provided with a sloping inner face 22, and all of the hone boxes 19 are yieldably restrained against outward radial movement relative to the head member 13 by upper and lower annular springs 23 and 24, respectively, engaging the outer surfaces of all of the hone boxes and being received in annular recesses 25 formed in the head member 13.

Received in the gauge slots 18 of the head member 13 are gauge boxes 27 and 28, respectively, which are preferably press-fitted or otherwise rigidly secured relative to the head member, and since the gauge boxes are identical in construction, only the gauge box 27 will be described in detail. The gauge box 27 is provided with a central opening 29 within which is positioned a U-shaped core 30 formed of magnetic material, on the upper leg of which is provided an upper winding 31 and on the lower leg of which is provided a lower winding 32, which windings are connected in series to form a first winding means 26. Inset in the outer face of the gauge box 27 in a suitable recess 33 is a closure member 34 formed of substantially nonmagnetic material, such as aluminum, which is rigidly secured relative to the gauge box, as by a press-fit. As will be noted, the U-shaped core 30 is positioned in the opening 29 so that the outer ends of the legs thereof almost engage the closure member 34. The gauge box 28 is provided with a second winding means 35 which is identical in construction with the first winding means 26 of the gauge box 27. The upper and lower windings 31 and 32 of the first winding means 26 are in series with each other and are connected in series through a conductor 36 with the coils of the second winding means 35 of the gauge box 28, which are also connected in series, and which are in turn connected to a lead-in wire 37. The other end of the first winding means 26 is connected to a lead-in wire 38. The conductor 36 and the lead-in wire 38 pass through a hold 39 drilled in the end of the gauge box 27, and the lead-in wires 37 and 38 pass outwardly from the major bore 14 through a hole 40 drilled in the head member 13 into a longitudinal channel 41 formed therein. As will be noted, when the head member 13 is disposed within the bore 11, the closure members 34 will be slightly spaced from the bore 11, forming air gaps 42 and 43 therebetween adjacent the outer ends of the legs of the cores of the first and second winding means 26 and 35. The air gaps 42 and 43 are variable in length, the same increasing as the honing operation, described hereinafter, progresses.

Received in the major bore 14 is a plunger member 44 having a rod 45 formed thereon which passes upwardly through the partition 16. The plunger member 44 is provided with a pair of longitudinal channels 46 therein, which are oppositely disposed and which fit around the gauge boxes 27 and 28, respectively, the channels being rectangular in cross-sectional configuration. Also formed in the plunger member 44 are hone box channels 47, each of which fits around one of the hone boxes 19, and each of which is provided with an inner face 48 which is tapered to

cooperate with the sloping inner face 22 of the corresponding hone box. Thus, downward movement of the plunger member 44 will cause each of the hone boxes 19 to move radially outwardly in its hone slot 17, to engage the bore 11 of the tubular member 10. Formed in the rod 45 is a longitudinal groove 50 which receives the inner end of a screw pin 51 threaded into a threaded opening 52 formed in the head member 13, the screw pin and the groove cooperating to form a stop means limiting axial movement of the rod 45. Threaded into the threaded minor bore 15 of the head member 13 is a tubular sleeve 54 having a longitudinal groove 55 cut therein to receive the lead-in wires 37 and 38, the upper ends of which are electrically connected to a suitable slip ring mechanism 56 adapted to be engaged by electrical contacting brushes (not shown), as is well known in the art, to form an electrical take-off for the lead-in wires. The slip ring mechanism 56 is carried on the upper end of the tubular sleeve 54. Provided on the tubular sleeve 54 is a collar 57 having a pin 57b therein which extends through a suitable hole in the sleeve into a plug 57c journaled therein, through which slidably passes a rod member 58, the lower end of which is threaded into the upper end of the rod 45, and the upper end of which passes outwardly through the upper end of the sleeve 54, there being a compression spring 59 positioned around the rod member 58 and engaging the rod 45 and the plug 57c. The compression spring 59 is set under compression so as to normally urge the plunger member 44 downwardly to move the hone boxes 19 outwardly into engagement with the bore 11 of the tubular member 10 against the action of the annular springs 23 and 24. By raising the rod member 58 against the action of the compression spring 59, however, the plunger member 44 will be moved upwardly so as to permit the annular springs 23 and 24 to retract the hone boxes 19 into the head member 13.

During operation, the tubular sleeve 54 is rotated or reciprocated, or both, by any suitable means (not shown), and, since the hone boxes 19 are forced outwardly by the plunger member 44, the hone elements 21 are maintained in pressure engagement with the wall of the bore 11 of the tubular member 10 by the action of the compression spring 59, causing honing of the bore as a consequence, which constitutes the honing operation of my device. As the honing operation progresses, the length of the space in the air gaps 42 and 43 between the closure members 34 and the bore 11 will increase, as described. If an alternating current potential is impressed across the series-connected first winding 26 and second winding 35, it will be clear that a magnetic circuit will be established through the U-shaped core 30, the closure member 34, and the tubular member 10 being worked, and that as the distances across the air gaps 42 and 43 become progressively greater with increased honing, the reluctance of the magnetic path will increase and the impedance of the series-connected windings 26 and 35 will vary proportionally.

This change in impedance of the series-connected windings 26 and 35 can be indicated at a remote point by use of a suitable electric circuit and a suitable indicating means. The circuit shown in Fig. 4 has been found to be very satisfactory. Referring thereto, the series-connected windings 26 and 35 are connected in series with a variable impedance 65 across a source of alternating potential of suitable frequency, indi-

cated at 66. The variable impedance 65 can be positioned at a point remote from the series-connected windings 26 and 35, and only the lead-in wires 37 and 38 need extend to the honing device. The variable impedance 65 may comprise a variable resistance, although I prefer to use a variable reactance having an impedance of the same order as the series-connected windings 26 and 35, so that the current and voltage in the two portions of the output circuit (to which the impedance 65 and the windings 26 and 35 are respectively connected as will be described) will have substantially the same phase relationship. The variable impedance 65 serves as an adjustment for the circuit, as will be described hereinafter.

A primary winding 67 of a transformer 68 is connected across the series-connected windings 26 and 35, and a similar primary winding 69 of a transformer 70 is connected across the variable impedance 65. The transformer 68 provides a secondary winding 71 which substantially matches in impedance a suitable rectifier 72 which is connected to one terminal thereof, the other terminal being connected to a conductor 73 and to one terminal of a secondary winding 74 of the transformer 70. The impedance of this winding matches that of a rectifier 75. In some instances, the transformers 68 and 70 can be eliminated in favor of a direct connection between the rectifiers 72 and 75 and the series-connected windings 26 and 35 and the variable impedance 65. In this event, the impedance of the series-connected windings 26 and 35 and the impedance of the variable impedance 65 should substantially match the impedances of the rectifying circuits to which they are connected. The output of the rectifying means comprising the rectifiers 72 and 75 as shown in Fig. 4 as being delivered to a resistor 76, the center tap of which is connected to the conductor 73. By-pass or filter condensers 77 and 78 may be connected across the halves of the resistor 76 to filter out the peaks and valleys of the rectified current.

The resistor 76 is connected to the input circuit of a suitable amplifier means. This should preferably be of the ortho-amplifier type for reasons to be hereinafter described. Fig. 4 shows diagrammatically a single-stage amplifier including a pentode tube 80, the grid 81 of which is connected to one terminal of the resistor 76.

A source of direct current potential is indicated as being applied across a voltage-dividing resistor 82. A movable contact 83 serves to connect one terminal of the resistor 76 to the resistor 82. A cathode 84 of the pentode tube 80 is shown as being of the indirectly heated type and is tapped into the resistor 82 at a point of appropriate potential, as is also a grid means 85 which may comprise the conventional screen grid. A plate 86 of the tube is connected by a conductor 87 to one terminal of a resistor 88, the other terminal of which is connected to the positive side of the direct current source, as indicated.

A suitable potential-responsive indicating means is connected to the output of the amplifier. This may comprise a galvanometer 90 connected between the conductor 87 and a variable contact 91 engaging the resistor 82. While various types of indicating means can be used in this connection, a galvanometer is particularly advantageous, not only because of its sensitivity but because it can be balanced to a zero reading and a pointer 92 thereof will deviate from this zero reading proportionally to the changes in diameter of the bore 11 produced by the hone. Furthermore, this deviation will be directional in that

deviations in one direction will indicate a diameter smaller than the calibrated standard, and deviations in the other direction will indicate a diameter larger than the calibrated standard. As the deviations produced are linear and proportional to the diameter of the bore 11, linear calibrations can be placed on the galvanometer 90 to obtain accurate indications of the diameter of the bore at any time during the honing.

As honing progresses during the honing operation, the potential input to the pentode tube 80 may not vary exactly proportionally with respect to changes in diameter of the bore, due to the fact that the construction of the control unit may be such that the potential across the series-connected windings 26 and 35 will not be directly proportional to changes in diameter, or due to other factors. The galvanometer 90 can be calibrated to compensate for this slight non-proportionality, but it is preferred to use a linearly calibrated meter and compensate for such slight non-proportionality by design of the amplifying unit, shown as comprising the tube 80. By proper design of the amplifier and by proper selection of the applied potentials, a characteristic amplifier curve can be obtained which, in the operating range of the device, will compensate for any non-proportionality and deliver an output potential which varies proportionally with the size of the bore 11 produced by the honing operation.

In using the device, the input to the tube 80 is first disconnected and the galvanometer 90 brought to a zero reading by adjustment of the variable contact 91. The input is then connected and the device is tested to be sure that displacements of the pointer 92 of the galvanometer 90 will vary proportionally with changes in diameter. This test can be made by inserting the hone in rings of known internal diameter, and if the pointer 92 does not move proportionally, suitable adjustment is made; for example, the movable contact 83 may be adjusted, or other potentials applied to the tube may be varied. The hone is then inserted in a ring of known internal diameter, for example, having the diameter of the bore which it is desired to obtain from the honing operation, and the variable impedance 65 is adjusted to bring the pointer 92 to a desired point, for example a zero reading. The device can then be inserted into the bore 11 to be honed, and the galvanometer 90 will indicate the deviation from the desired diameter in the vicinity of the hone elements 21, and honing can be effected until the galvanometer indicates that the desired diameter has been reached.

The electrical circuit shown in Fig. 4 is more fully described and claimed in my copending application, Serial No. 350,939, filed August 3, 1940, to which reference is hereby made for a better understanding of the operation and control of such a circuit.

Since the cores 30, on which the windings 26 and 35 are placed, are diametrically disposed, the head member 13 need not be accurately aligned axially with the axis of the bore 11 of the tubular member 10 to be honed, as errors in centering will be substantially cancelled by an increase in impedance of the windings 26 and a corresponding decrease in impedance of the windings 35, or vice versa, which is another important feature of my invention. It is also to be noted that the device shown in Figs. 1, 2, and 3 will operate only where the tubular member 10 is formed of magnetic material, as a magnetic flux from the cores 30 must pass therethrough. Where the tubular member 10 is formed of non-magnetic material,

or material which is substantially non-magnetic, an alternative embodiment of my invention, described hereinafter, may be used.

Referring to Figs. 5 and 6, I show an alternative form of gauge mechanism for use in my honing device, which is operated by a suitable movable armature engaging the inner wall of the tubular member to be worked so that the device may be used in working non-magnetic materials. Since the construction shown in Figs. 5 and 6 is substantially the same generally as the construction shown in Figs. 1, 2, and 3, the same numerals will be used to indicate corresponding parts with the suffix *a* added thereto. As shown in Figs. 5 and 6, I provide gauge boxes 27*a* and 28*a*, substantially similar to the gauge boxes 27 and 28, and since the gauge boxes 27*a* and 28*a* are identical with each other, only the gauge box 27*a* will be described. The gauge box 27*a* is provided with a closure member 34*a* suitably secured relative to the gauge box and having provided therein an armature opening 100 through which the outer end 101 of an armature 102 extends, the armature 102 being formed of magnetic material. On the armature 102 is formed a block member 103 having attached thereto a U-shaped spring 104 which is secured to one end wall of the gauge box 27*a* by suitable bolts 105, so as to support the armature for substantially axial movement. A coil spring 106 is provided between the inside leg of the U-shaped spring 104 and the inner wall of the gauge box 27*a* so as to normally urge the armature 102 outwardly through the armature opening 100, a stop screw 107 being provided to limit outward movement of the armature by engagement with the outer leg of the U-shaped spring 104. Suitably positioned in the gauge box 27*a* is a core 108 formed of magnetic material and of U-shape, having an outer leg 109 and an inner leg 110 longer than the outer leg by approximately the dimension of the armature 102, providing a fixed air gap 111 and a variable air gap 112 between the outer and inner legs 109 and 110, respectively, of the core 108 and the armature 102. Provided on the core 108 is a first winding 113 connected in series with a second winding 114 in the gauge box 28*a* by a conductor 36*a*, the outer end of the first winding being connected to a lead-in wire 37*a* and the outer end of the second winding being connected to a lead-in wire 38*a*, so as to connect in series the first and second windings. As will be noted, the conductor 36*a* and the lead-in wire 38*a* pass through a slot 115 formed in a central portion 116 of the plunger member 44*a* between the longitudinal channels 46*a*.

Hone boxes 19*a* are provided in the head member 13*a* similar to the hone boxes 19, and are provided with hone elements 21*a* adapted to engage the bore 11*a* of the tubular member 10*a*, as described in connection with Figs. 1, 2, and 3, the hone boxes 19*a* being moved radially outwardly by axial movement of the plunger member 44*a* as previously described.

In operation of the embodiment shown in Figs. 5 and 6, as the honing by means of the hone elements 21*a* progresses, the armatures 102 will move outwardly in response to the action of the coil springs 106 on the U-shaped spring 104 to increase the space between the inner end of the

armature and the inner leg 110 of the core 108, thus increasing the distance across the air gap 112. If an alternating current potential is impressed across the first winding 113, it will be clear that a magnetic flux will be set up through the core 108, the fixed air gap 111, the armature 102, and the variable air gap 112, and that as the armature 102 moves outwardly in response to an increase in diameter of the bore 11*a* caused by the honing operation so as to increase the distance across the air gap 112, the reluctance of such magnetic path will increase and the impedance of the winding 113 will vary proportionally. Since the windings 113 and 114 are series-connected, it will be clear that the electrical circuit shown in Fig. 4 may be utilized in the same manner as described hereinabove to indicate on the galvanometer 90 variations in the diameter of the bore 11*a* due to the honing operation, it being evident that the windings 113 and 114 are substituted for the windings 26 and 35, respectively, shown in Fig. 4.

Throughout the foregoing specification I have referred to the operation of my device as a "honing operation" for the purpose of illustration, but it will be appreciated by those skilled in the art that the invention may equally well be utilized in grinding or other similar operations. Consequently, I hereby define, for the purpose of this specification and the claims attached hereto, that the term "honing" as used herein shall mean honing, grinding, boring, or other method of removing material from a member to be worked.

Although I have shown and described a preferred form of my device, and an alternative embodiment, it will be appreciated that certain parts and units thereof, and of the electrical circuit shown in Fig. 4, are merely equivalents of certain other parts or elements which may be substituted therefor without the exercise of invention, and accordingly I do not intend to be limited to the disclosure herein, but wish to be afforded the full scope of the following claim.

I claim as my invention:

45 In a gauge device adapted to indicate a dimension of a member, the combination of: a head element; a first gauge element including a first coil, said first gauge element being so constructed and arranged that a variation in the distance of 50 said first coil from one side of the member varies the electrical impedance of said first coil; first box means containing said first gauge element and removably secured to said head element; a second gauge element including a second coil, said second gauge element being so constructed and arranged that a variation in the distance of said 55 second coil from the other side of the member varies the electrical impedance of said second coil, said coils being connected in series so that 60 upon lateral movement of said head element relative to said member the impedance of said coils will vary by amounts that are equal and opposite; second box means containing said second gauge element and removably secured to said head element; means for impressing an electric potential across both said coils; and indicating means for measuring changes in the total impedance of said coils so as to indicate said dimension of the member.

RICARDO MESTAS.
